(57) **CLAIM**

The ornamental design for a brush with handle, as shown
and described.

DESCRIPTION

FIG. 1 is an elevation view of the brush with handle.

FIG. 2 is an elevation view of the other side of the brush with
handle.

FIG. 3 is a top view of the brush with handle.

FIG. 4 is a bottom view of the other end of the brush with
handle.

FIG. 5 is a rear view of the brush with handle; and,

FIG. 6 is a front view of the brush with handle.

The broken line outline representing bristles, is for illustra-
tive purposes only and forms no part of the claimed design.
